DESIGN FOR A POUNDING TOY

Samuel L. Beder, New York, N. Y.

Application October 24, 1945, Serial No. 123,152

Term of patent 7 years

(Cl. D34—15)

To all whom it may concern:

Be it known that I, Samuel L. Beder, a citizen of the United States, residing at 3150 Rochambeau Avenue, Borough of Bronx, city of New York, county of Bronx, and State of New York, have invented a new, original, and ornamental Design for a Pounding Toy of which the following is a specification, reference being had to the accompanying drawing, forming part thereof.

Figure 1 is a perspective view of a pounding toy showing my new design; and

Figure 2 is an elevational view of the pounding toy shown in Figure 1 on a reduced scale in inverted position.

I claim:

The ornamental design for a pounding toy, substantially as shown.

SAMUEL L. BEDER.
